UNITED STATES PATENT OFFICE.

EDWARD S. WINCHESTER, OF DORCHESTER, MASSACHUSETTS.

LATCH.

SPECIFICATION forming part of Letters Patent No. 416,309, dated December 3, 1889.

Application filed February 14, 1889. Serial No. 299,900. (No model.)

To all whom it may concern:

Be it known that I, EDWARD S. WINCHESTER, of Dorchester, in the county of Suffolk and State of Massachusetts, have invented 5 certain Improvements in Door-Latches, of which the following is a specification.

My invention relates to that class of latches in which the latch-bolt is held in a retracted position against the influence of a spring and 10 is automatically released and permitted to be projected when the door encounters the jamb in closing.

The invention consists, essentially, of a pivoted latch-bolt held in a retracted position 15 against the influence of its projecting spring by a detent, combined with a releasing device adapted to be operated by the door encountering the jamb.

The invention further consists in an im- 20 proved bearing for the spindle of the knob, whereby lateral or rocking motion of the same is avoided.

It also consists in certain details of construction and combinations of parts herein- 25 after fully set forth.

In the accompanying drawings, Figure 1 is a horizontal section of a latch, showing a portion 30 of the door-jamb, the latch-bolt being shown in a retracted position. Fig. 2 is a plan view of the same partly in section, some of the parts being removed to expose the internal mechanism to view. Fig. 3 is a perspective view of the lock and the door-jamb, showing the projecting plate thereon. Fig. 35 4 is a transverse section on the line $\alpha - \alpha$ of Fig. 1. Fig. 5 is a perspective view of the pivoted latch with its projecting spring. Fig. 6 is a perspective view of a modified form of the detent.

40 Referring to the drawings, A represents a portion of a door; B, a portion of the door-jamb; C, the latch-case having, as usual, the inner and outer walls c and c' and the end wall c^2 .

45 D and D' represent the inner and outer knobs, respectively, provided, as usual, with the spindle d and shank d' , the latter adapted to receive the spindle, which is passed therethrough and screwed or otherwise fastened 50 to the knob D. The shank is provided, as usual, with the tumblers e e' , by means of

which the latch is retracted, as more fully described hereinafter.

E represents a strong spiral spring encircling the spindle between the shank and the 55 knob D'.

F represents the latch-bolt consisting of the base f , the two side walls f' and f^2 , and the end wall f^3 . This latch is pivoted in the end to the casing of the lock by means of a pivot- 60 pin g , which passes through the latch-bolt and is fixed to the casing C. This latch is adapted to be projected through a recess in the end of the casing to an operative position or be retracted flush with the said casing in 65 an inoperative position.

G represents a coiled spring encircling the pin g , by which the latch-bolt is projected. This spring is provided with the loop g' , which bears upon the latch-bolt and the two 70 arms g^2 and g^3 , which extend upward, as shown in Fig. 1, and when the latch-bolt is in a retracted position bear against the inner casing of the latch.

In order that the latch-bolt may be sus- 75 tained in a retracted position, as shown in the drawings, I provide the same with the bar h , extending between the side walls thereof. This bar is constructed to be engaged by the spring-detent H, fixed at one end to the cas- 80 ing C and having its other end free. The free end of this detent is provided with a notch h' , adapted to extend beneath the bar h on the latch-bolt, and thus hold the same in a retracted position. In order that the de- 85 tent may be lifted out of contact with the latch-bolt to release the same, I provide the sliding plate I. As shown, this plate is mounted in the forward edge of the casing, and is provided with the central tongue i , extending 90 between the walls of the latch-bolt in contact with the free end of the detent. On each side of the central tongue i the plate is pro- 95 vided with the tongues or fingers i' and i^3 , which extend on either side of the latch-bolt and serve as a means of guiding the plate. The end of the plate is provided with the enlarged bearing-surface k , adapted to encounter the projection L, formed on a plate se- 100 cured to the jamb B of the door by means of screws or otherwise.

M represents a bail consisting of the two

arms m and m' , pivoted at one end to the walls of the latch by pins m^2 , and connected at their other ends by a cross-bar m^3 , which extends beyond the arms on either side. The 5 ends of this cross-bar are adapted to be engaged by projections o and o' , formed on the inner edges of the sliding frames P and P' . These frames P and P' extend lengthwise of the lock, and are urged constantly forward 10 by spiral springs n and n' , located therein and encircling headed bolts n^2 and n^3 , one end of these springs bearing on the heads of the bolts and their other ends bearing on the frame. These frames are further provided 15 with the projections p and p' , adapted to be engaged by the tumblers e and e' , and by means of which the frames may be retracted by the rotation of the knobs, the springs acting to turn the frames and knobs to their 20 former position.

The operation is as follows: The parts being in the position shown in Fig. 1, with the latch in a retracted position, when the door is closed the projection L will encounter the 25 end of the plate and will force the same inward, thus pushing back the spring-detent H from beneath the bar on the latch-bolt, which, being released, will be projected by its spring G outward into the recess in the door-jamb. 30 When it is desired to unlatch and open the door, the knobs being rotated, the tumblers carried thereby will draw one of the frames against the influence of its spring, which, by means of its lateral projection encountering 35 the cross-piece of the bail, will draw the latch-bolt inward until the bar thereon passes beyond the notch on the spring-detent. The knob is then released and is restored to its former position by the spring-frame. 40 It is not essential that the bar h should be located between the walls of the latch-bolt, as any construction may be employed which will operate, as shown, to engage the spring-detent and retain the latch-bolt in a retracted 45 position. As shown in Fig. 3, the edge of the casing is recessed to admit the projection L , and to prevent the same from encountering the edge of the casing I commonly cover this recess with a thin plate t to present a 50 finished appearance. By employing this covering I am enabled to place the projection L very close to the edge of the jamb, which for many reasons is advantageous.

In Fig. 6 I have represented a modification 55 of my detaining-spring. In this case the spring is provided with two notches, in order

that the latch may be held either wholly or partially retracted.

On reference to Fig. 1 it will be seen that the shank of the knob D is long and extends 60 quite a distance beyond the casing of the latch. This forms a good bearing for the spindle and prevents the same from wabbling or being forced out of line by the spring located between the shank and the knob. 65

Having thus described my invention, what I claim is—

1. In a door-latch, the combination, with the case, of the pivoted latch-bolt having the recess therein, a bar located within said recess, a spring detent or catch arranged to engage the bar and retain the latch-bolt in a retracted position, and a lateral releasing device acting on said detent to lift the same out of engagement with the bar. 75

2. The latch-case, the sector-shaped bolt pivoted at one end and arranged to swing inward and outward at the opposite end, its projecting spring, the shouldered spring-detent directly engaging the swinging end of the 80 latch to hold the same in its retracted position, and the trip-pin acting at one end against the detent and exposed at the opposite end, said parts constructed and arranged in relations substantially such as described and 85 shown.

3. In combination with a sector-shaped pivoted swinging bolt and its projecting spring, a spring-detent provided with a plurality of shoulders to successively engage the bolt and 90 hold the same in different positions, and the trip device.

4. In combination with the case, the pivoted sector-shaped bolt recessed in its inner side, the spring-detent attached to the case 95 and engaging within the bolt, and the sliding trip I , having one end exposed and the opposite end projected into the interior of the bolt to release the detent.

5. In a latch, the combination, with the 100 spindle, of the shank surrounding said spindle and extending through and beyond the casing of the latch, and the spring located between the spindle and the shank.

In testimony whereof I hereunto set my hand, 105 this 21st day of January, 1889, in the presence of two attesting witnesses.

EDWARD S. WINCHESTER.
